UNITED STATES PATENT OFFICE.

STEPHEN A. MISCHANSKY, OF SYRACUSE, NEW YORK, ASSIGNOR OF ONE-HALF TO
STANISLAW LNISKI, OF SYRACUSE, NEW YORK.

PHOTOGRAPHIC DEVELOPING APPARATUS.

1,222,654.

Specification of Letters Patent. Patented Apr. 17, 1917.

Application filed May 11, 1915. Serial No. 27,378.

To all whom it may concern:

Be it known that I, STEPHEN A. MISCHANSKY, a subject of the Emperor of Austria, and a resident of Syracuse, in the county of Onondaga, in the State of New York, have invented new and useful Improvements in Photographic Developing Apparatus, of which the following, taken in connection with the accompanying drawings, is a full, clear, and exact description.

This invention relates to certain improvements in apparatus for developing photographic films in broad daylight or at any time and in any locality where such operations may be necessary or desirable.

The main object is to provide a light and easily portable apparatus of this character in which a film of any ordinary length, such as commonly used in cameras, may be quickly and effectively developed and fixed without exposure or removal from the apparatus.

These films are usually rolled together with a suitable opaque paper upon a spool or reel, and another object of my invention is to provide suitable means for stripping the paper from the film simultaneously with the unreeling of the film into one of the compartments of the developing apparatus, thereby avoiding the preliminary operation of removing the paper prior to the insertion of the reel in said apparatus.

A further object is to provide means whereby the film may be rendered visible without exposure to actinic light in transit from one compartment to another of the developer case.

Other objects and uses relating to specific parts of the device will be brought out in the following description.

In the drawings—

Figure 1 is a perspective view of a portable daylight developing apparatus, embodying the various features of my invention.

Fig. 2 is an enlarged longitudinal vertical sectional view of the same apparatus, taken on line 2—2, Fig. 1.

Fig. 3 is an enlarged transverse vertical sectional view taken on line 3—3, Fig. 1.

Figs. 4 and 5 are enlarged transverse vertical sectional views taken, respectively, on lines 4—4 and 5—5, Fig. 1, except that in Fig. 4 the doors or lids for the sight and light openings are open.

Fig. 6 is a perspective view of the detached reel container.

Fig. 7 is a perspective view similar to Fig. 1 of a modified developing apparatus, showing an all-metal case.

Figs. 8 and 9 are a longitudinal vertical sectional view and a transverse vertical sectional view, taken, respectively, on lines 8—8 and 9—9, Fig. 7.

The apparatus shown in Figs. 1 to 6, inclusive, comprises a substantially rectangular box or case —1— of any suitable dimensions or material, but in this instance of wood having bottom, side and end walls rigidly united and a removable top —2—, the interior of the case being divided by partitions —3— into opposite end compartments —4— and —4'— and an intermediate compartment —5—, as shown more clearly in Fig. 2, said partitions —3— being preferably rigidly united to the bottom and sides parallel with the ends so that the compartments are substantially rectangular.

The cover —2— is removably mounted upon the upper edges of the ends and sides of the case —1— and is held in operative position by apertured spring catches —6— normally interlocked with pins —7—, the spring catches being secured to the ends of the case —1—, while the pins —7— are secured to the cover, whereby the upper ends of the spring catches may be forced outwardly out of interlocking engagement with the pins —7— to permit the removal of the cover and all parts covered thereby.

The portions of the cover directly over the compartments —4— and —4'— are provided with ledges —8— extending from side to side and inwardly toward each other from the ends of the case part way only across their respective compartments, leaving openings —9— and —9'—, the opening —9— serving to permit the introduction of a fixing solution, while the opening —9'— may serve a similar purpose for the developing liquid, but is primarily for the purpose of allowing the passage of the film, as —a—, therethrough in transit to the compartment —9— in a manner hereinafter described.

The opening —9— is normally covered by a sliding gate or shutter —10— guided in suitable ways —11— on the opposite sides of the cover and of sufficient area to effectively close the opening —9— against the entrance of light, but which may be drawn

back across the upper face of the ledge —8— when introducing the fixing solution into the adjacent compartment —4—, the slide —10— being provided with a suitable handle piece —12— by which it may be operated.

5 The cover —2— is also provided with an opening registered with the compartment —4—, but adapted to be closed by a hinged lid or shutter —13— to exclude light from the interior of said compartment —4— when the reel-supporting case as —14— is removed, said lid being provided with a suitable handle —15— by which it may be operated.

15 The central portion of the cover is also provided with a sight-opening —16— registering with the compartment —5— and normally closed by a hinged shutter —17— to exclude light from said compartment, said shutter being held in operative position by a movable catch —18— on the main body of the cover, as shown more clearly in Figs. 1 and 4.

25 The compartment —5— constitutes what may be termed a "light chamber" having a light opening —19— in one side provided with a door or closure —20— which is hinged to the case at the lower side of the opening to swing outwardly and downwardly, but is 30 preferably opened when transferring the film from the developer container to the fixing bath and at other times may be held in its closed position by a suitable catch —21— having an external hand-piece —22— by 35 which it may be operated.

The top of the compartment is covered by a screen —23— of colored glass or equivalent transparent substance, preferably red or orange, while the sight opening —16— in 40 the cover is also provided with a similar screen —24— extending thereacross in parallelism with and spaced apart from the screen —23— so as to form an intervening dark room or chamber through which the 45 film may be drawn from one compartment to the other without exposing it to actinic rays while the screens —23— and —24— permit the interposed portion of the film to be viewed or inspected at will by simply 50 opening the door —20—.

Within the compartment is placed a mirror or other reflecting medium —25— inclining upwardly and rearwardly from the lower side of the light opening —19— so 55 as to reflect the light upwardly through the screens —23— and —24—, thus permitting the operator to inspect the film through the screens —24— and —23— when the shutter —17— is opened, as for example in transferring the film from the developer bath to the washing or fixing bath.

By this means for viewing the developed film, the operator may easily determine at a glance through the screens whether or not the 60 photographic matter is properly developed

and if not, the film may be returned to the developer tray without exposure.

Separate containers —26— and —26'— are removably mounted within their respective compartments —4— and —4'— between the end walls of the case and partitions —3—, said containers being of sufficient size to substantially fill their corresponding compartments and adapted to receive suitable reels —27— and —27'— to 75 which the opposite ends of a flexible conveyer —28— are attached for feeding the film from one compartment or container to the other.

These reels —27— and —27'— are provided with removable shafts —29— which are journaled in suitable bearings in opposite sides of their respective containers and are normally locked to their respective reels by keys or pins —30—, one end of each shaft 80 being extended through and journaled in a suitable bearing in one side of the case —1— and provided with an external hand-crank —31— by which it may be operated for the purpose of winding the carrier —28— with 85 the film thereon from one reel to the other and vice versa.

The film conveyer —28— preferably comprises two narrow strips of rubber, fabric or other flexible material spaced some distance apart in parallelism to correspond approximately to the width of the film for engaging the extreme outer edges of the same without liability of injuring the photographic matter thereon, and preferably 95 wound upon the ends of their respective reels —27— and —27'—, as shown more clearly in Fig. 3, the intermediate portion of the carrier being guided by curved bearings —32— on the outer face of the opposite 100 ends of the partitions —3— close to the upper edges thereof to travel lengthwise across the upper face of the screen —23— or rather through the space between the screens —23— and —24—.

110 The undeveloped film is usually protected by a strip —33— of opaque or equivalent paper of substantially the same width as, but of greater length than the film and which is usually rolled with the film upon a reel or spool —34— which is inclosed within the case —14—, previously mentioned.

When it is desired to develop the photographic matter upon a film, the door —13— is opened to the position shown in Fig. 2 115 and the reel case —14— with the reel —34— containing the film and its protective strip —33— is mounted in its stead upon suitable supporting ledges —35— on opposite sides of the case within the opening —9'—, the 120 opposite sides of the case being provided with lengthwise flanges —36— resting upon the ledges —35— and adapted to be engaged by movable catches or detents —37— for holding the reel case in operative position, the 125

same catch also serving to hold the door —13— closed when the reel case is removed.

The reel case is preferably made of sheet metal and light-tight and its main body is 5 circular in cross section, except that its lower side is provided with an opening to permit the insertion and removal of the reel —34—, said open side being normally closed by a hinged closure —38—, as shown more clearly 10 in Figs. 2 and 6.

A shutter —39— is hinged to the exterior of the reel case —14— to effectively close the remaining portion of the opening —9'— so that when the entire reel case is adjusted for 15 use, the joints with the main body of the cover are light-tight, as shown more clearly in Fig. 2.

A light-excluding shutter —40— is hinged to the cover —2— at the inner edge of the 20 opening —9'— and preferably has its inner edge made of pliable material, such as soft rubber or felt, to bear against the film as it is drawn from the reel —34— between the screens —23— and —24—, thereby holding 25 the film flatwise in contact with the conveyer —28—.

The opposite strips of the conveyer belt —28— are connected by cross bars —41— which hold them in spaced relation and also 30 serve to receive attaching hooks —42— with which the attaching strips on the ends of the film may be interlocked to cause the conveyer to draw the film from one compartment or container to the other.

35 The inner portion of the reel case —14— within the opening —9'— is provided with a plurality of, in this instance three, parallel rollers —43—, —44— and —45—, extending transversely of the cover within said opening 40 for guiding the film from the reel —34— and also for guiding and stripping the protective strip —33— from the film; for example in adjusting the film preparatory to developing the same, the free end of the film 45 and corresponding end of the strip —33— are drawn by hand between the rollers —43— and —44—, the free end of the film being attached to the hooks —42— on the conveyer —28—, while the corresponding end of the protective strip —33— is drawn 50 between the rollers —44— and —45— and across the under side of the closure —38— and thence upwardly through the opening —9'— to the exterior of the case at the outer 55 side of the reel case —14—, so that by rotating the reel —27— in the direction indicated by arrow —x— Fig. 2, the conveyer with the film attached thereto will be wound from the reel —27'— upon the reel —27— until 60 the film is entirely withdrawn from the spool —34—, whereupon the opposite end of the film carrying a suitable attaching strip may be attached to the hooks —42— on the portion of the conveyer adjacent the reel 65 —27—, it being understood that when the

film is wound upon the reel —27—, the whole portion thereof bearing the photographic matter will have been carried beyond the shutter —40—, thus permitting the reel case with the spool —34— therein to be 70 removed and the adjacent end of the film attached to the conveyer in the manner just described without exposing the film.

After the film has been reeled upon the reel —27— in the container —26— and the 75 reel case —14— with the spool —34— therein is removed, the developing liquid may be introduced into the container —26'— through the opening —9'—, whereupon the lid —13— may be closed and locked so as to 80 render the joints light-tight and the reel —27— is then operated in the direction indicated by arrow —y— to wind the carrier and film thereon from the reel —27—, it being understood that the carrier —28— is 85 sufficiently longer than the film beyond the ends thereof to allow the entire film to be wound upon either reel, thereby permitting all of the photographic matter on the film to be treated in the developing liquid. 90

After the film has been wound upon the reel —27— in the manner just described, the sliding gate —10— may be opened and a suitable quantity of fixing solution may be introduced into the container —26— 95 through the inlet —9— and the gate —10— may then be closed to exclude light, whereupon the film may be rewound upon the reel —27— to subject the same to the fixing solution directly from the developer. This 100 fixing of the film directly from the developing liquid has been found to be practicable without the usual washing.

In Figs. 7 to 9, inclusive, I have shown a modified form of my invention consisting of 105 an all-metal case —1'— having end compartments —50— and —50'— which also constitute the containers for the developing liquid and fixing solution, as distinguished from the wood case having the removable 110 containers, the case —1'— being provided with a removable metal top —2'— having openings —9— and —9'— registering with the upper open ends of their respective compartments —50— and —50'— and also having 115 a central sight-opening —16'— registering with the light compartment —5—.

The openings —9—, —9'— and —16'— are provided with suitable light-tight closures —10'—, —13'— and —17'—, all hinged to 120 one and the same side of the top and having their opposite sides provided with spring clasps —52— engaging with a rib —53— on the adjacent side of the case for holding them in their closed positions. Otherwise, 125 the construction and operation is quite similar to that previously described.

What I claim is:

1. In a photographic developing apparatus, a case having a developing chamber in 130

one end and a fixing chamber in the other end, and a "dark-chamber" intermediate the first-named chambers and communicating therewith to permit the passage of the film from one of said chambers to the other, said first-named chambers being provided with separate inlets for their respective liquids, and separate closures for said inlets.

5. In a photographic developing apparatus, a case having a developing chamber in one end and a fixing chamber in the other end, and a "dark-chamber" intermediate the first-named chambers and communicating therewith to permit the passage of the film from one of said chambers to the other, said first-named chambers being provided with separate inlets for their respective liquids, and separate closures for said inlets, and separate reels located in said first-named chambers.

10. In a photographic developing apparatus, a case having a developing chamber in one end and a fixing chamber in the other end, and a "dark-chamber" intermediate the first-named chambers and communicating therewith to permit the passage of the film from one of said chambers to the other, said first-named chambers being provided with separate inlets for their respective liquids, and separate closures for said inlets, separate reels located in said first-named chambers, and a conveyer apron having its opposite ends attached to said reels and its intermediate portion extended through the "dark-chamber."

15. In a photographic developing apparatus, a case having a developing chamber in one end and a fixing chamber in the other end, and a "dark-chamber" intermediate the first-named chambers and communicating therewith to permit the passage of the film from one of said chambers to the other, said first-named chambers being provided with separate inlets for their respective liquids, and separate closures for said inlets, from one of said chambers to the other, said

first-named chambers being provided with separate inlets for their respective liquids, separate closures for said inlets, and a movable shutter at one end of the "dark-chamber" for excluding light from said chamber when the closure for the adjacent inlet is open.

20. In a photographic developing apparatus, the combination of a case having a chamber in one end for a developing liquid and a separate chamber in the opposite end for a fixing liquid, said case having a "dark-chamber" between the first-named chambers, the "dark-chamber" having lower and upper screens in spaced relation to exclude actinic rays from the "dark-chamber" and to form a passage for the film from one of the first-named chambers to the other, and means for admitting and cutting off light from the under side of the lower screen.

25. In a photographic developing apparatus, the combination of a case having a chamber in one end for a developing liquid and a separate chamber in the opposite end for a fixing liquid, said case having a "dark-chamber" between the first-named chambers, the "dark-chamber" having lower and upper screens in spaced relation to exclude actinic rays from the "dark-chamber" and to form a passage for the film from one of the first-named chambers to the other, means for admitting and cutting off light from the under side of the lower screen, and means for admitting and cutting off light from above the upper screen.

In witness whereof I have hereunto set my hand this 3d day of May, 1915.

STEPHEN A. MISCHANSKY.
